UNITED STATES PATENT OFFICE.

THOMAS STEVENS TOWLE, OF STANTON, MICHIGAN.

ACETYLENE-GAS GENERATOR.

No. 919,091.

Specification of Letters Patent.

Patented April 20, 1909.

Application filed October 29, 1908. Serial No. 460,020.

To all whom it may concern:

Be it known that I, THOMAS S. TOWLE, a citizen of the United States, and a resident of Stanton, in the county of Montcalm and State of Michigan, have invented a new and Improved Acetylene-Gas Generator, of which the following is a full, clear, and exact description.

This invention relates to carbide holders employed in the generation of a volume of acetylene gas as a motive agent for portable engines, and more particularly for automobile vehicles; and the purpose of the invention is to provide novel details of construction for a carbide holder, that afford a compact, convenient device of the character indicated, which is positive in its action for the removal of spent residuum and the constant exposure of fresh carbide to water jets, thus insuring a uniform generation of gas for supply as a motive agent.

The invention consists in the novel construction and combination of parts, as is hereinafter described and defined in the appended claims.

Reference is to be had to the accompanying drawings forming a part of this specification, in which similar characters of reference indicate corresponding parts in all the views.

Figure 1 is a side view of a water supply tank, a residuum receiver hung from the tank, and the improved carbide holder held in the receiver and exposed to view by the removal of a part of the side wall of said receiver; Fig. 2 is an enlarged sectional side view of the improved carbide holder; and Fig. 3 is a plan view of the holder, from which the carbide has been removed.

In the usual construction of a gas generator for a portable engine or automobile vehicle using acetylene gas as a motive agent, a water tank such as is indicated by the numeral 5 in Fig. 1, is employed. The tank 5 is usually cylindrical in its side wall, and in the present form thereof, is provided with a filler opening closed by a cap *a* and also is furnished with a discharge nozzle *b* and an air vent cock *c*. The bottom wall 5^a of the water holding tank 5, is secured within the side wall thereof a short distance above the lower edge of the latter, and inside of the depending circular flange thus produced, the upper edge of a cylindrically-walled receiver 6, is fitted.

From the exterior of the receiver 6, at opposite points near the upper edge thereof, two ears *d* project, whereon the lower ends of

two hanger rods 7 are pivoted, said rods which extend up at the outer side of the tank 5 and pass through bracket plates *e*, that overhang the periphery of the tank at its upper end, receive nuts *g* on their threaded ends, and it will be noted that a screwed adjustment of the nuts in a proper direction will impinge the upper edge of the receiver 6 upon the bottom wall 5^a of the tank 5.

The carbide holder that is the essential feature of the invention, comprises a cylindrically-walled receptacle formed of suitable plate metal, having a foraminated bottom wall 8^a which is secured on the side wall 8 that is also numerously perforated, as shown at *h* in the drawings. The diameter of the cylindrical wall 8 of the carbide holder, is so proportioned with relation to the inner diameter of the receiver 6, that when placed centrally therein, an annular space *i* of suitable width will be afforded between said parts, as shown clearly in Fig. 1. There are a suitable number of short legs *m* secured on the bottom wall 8^a, that serve to support the holder so as to produce a space *i'* between the bottom wall of the receiver 6 and that of the holder.

The carbide holder is open at its upper end, and the defining edge of the side wall 8 is reinforced by securing a stout wire ring thereon, as shown at *n* in Fig. 2. Centrally on the bottom wall 8^a of the carbide holder, a hollow cylindrical post 9 is erected and secured, said post having the upper end thereof covered with a conical deflector 9^a. Above the conical deflector 9^a, a cylindrically-walled chamber 10 is formed or secured on the post 9, which extends to a point near the upper edge of the holder wall 8. In the wall of the chamber 10 for a distance above the conical deflector 9^a, a large number of spaced perforations *o* are formed, this series of small holes extending up about one half the height of the chamber 10. Upon the upper edge of the cylindrical chamber 10, a dished radial flange 10^a is secured, that serves as a shallow funnel for the introduction of water into the chamber 10. The space around the post 9 and the chamber 10, is filled with calcium carbide A in small fragments, as is shown in Fig. 2.

In operation, drops of water fed from the tank 5, fall in succession upon the conical deflector 9^a and are thence deflected laterally toward the perforated wall of the chamber 10. The sprayed water passes through the

perforations *o* and moistens the carbid adjacent thereto. By capillary attraction, the sprayed water is caused to pervade the mass of carbid adjacent to the deflector 9^a and by 5 chemical action generates acetylene gas, that is conducted from the generator to a point for use as a motive agent.

The sprayed introduction of water laterally into the carbid holder, may be graduated so as to control the amount or volume 10 of gas evolved from a decomposition of the carbid, by regulating the feed of water down into the chamber 10. The saturation of the carbid is downward, and when the carbid 15 is consumed that is in the holder below the conical deflector and converted into powdered residuum, the motion of the vehicle will so jolt the carbid holder that the waste material will be sifted through the side wall 20 8 and the bottom wall 8^a of the holder. This removal of the refuse matter permits the carbid that was above the deflector 9^a to descend by its gravity, and present a fresh supply of the carbid for conversion into gas as 25 before explained.

By providing means for the spraying introduction of water, a short distance above the bottom of the carbid holder, excessive saturation of the carbid and of the residuum 30 is obviated, which is essential for the continuous evolution of gas until the carbid supply in the holder is exhausted, or the water feed is stopped, which will control the generation of the gaseous motive agent.

35 It is obvious that the receiver and carbid holder may have rectangular forms and be equally as effective in service. Further the generator may be increased in dimensions for the reception of more than one water 40 feeding device and the consequent evolution of a greater volume of gas.

Having thus described my invention, I claim as new and desire to secure by Letters Patent:

1. In a device of the class described, a wa- 45 ter tank, a receiver having an open top, means for clamping the open top of the receiver against the bottom of the tank, a car- 50 bid holder in the receiver, said carbid holder having perforate side and bottom walls and 55 an open top, and having its walls spaced apart from the walls of the receiver, a cham- 60 ber at the center of the holder, a conical de- 65 flector spaced above the bottom of the carbid holder within the chamber, said chamber having its side walls perforated above the deflector, means in the bottom of the tank 70 for supplying water to the chamber, said chamber having a flaring top for engaging the bottom of the tank, said top encircling 75 the water supply means.

2. In a device of the class described, a wa- 45 ter tank, a receiver having an open top, means for clamping the open top of the receiver against the bottom of the tank, a carbid 50 holder in the receiver, said carbid holder having perforate side and bottom walls and 55 an open top, and having its walls spaced apart from the walls of the receiver, a cham- 60 ber at the center of the holder, a conical de- 65 flector within the chamber, said chamber having its side walls perforated above the deflector, and means in the bottom of the tank 70 for supplying water to the chamber.

In testimony whereof I have signed my 75 name to this specification in the presence of two subscribing witnesses.

THOMAS STEVENS TOWLE.
